DESIGN FOR A LIGHT CASING FOR A SUCTION CLEANER OR SIMILAR ARTICLE

Bernard C. Becker, Canton, Ohio, assignor to The Hoover Company, North Canton, Ohio, a corporation of Ohio

Application August 11, 1933. Serial No. 48,994

Term of patent 14 years

To all whom it may concern:

Be it known that I, BERNARD C. BECKER, a citizen of the United States, residing at Canton, in the county of Stark and State of Ohio, have invented a new, original, and ornamental Design for a Light Casing for a Suction Cleaner or Similar Article, of which the following is a specification, reference being had to the accompanying drawing, forming part thereof.

In the drawing:

Figure 1 is a side view of the light casing for a suction cleaner or similar article, showing my new design; and

Figure 2 is a view from an angle between the front and the side of the casing.

I claim:

The ornamental design for a light casing for a suction cleaner or similar article, as shown.

BERNARD C. BECKER.
